UNITED STATES PATENT OFFICE.

JOHN F. MYERS, OF SAN FRANCISCO, CALIFORNIA.

DESIGN FOR A LAMP-STOVE.

SPECIFICATION forming part of Design No. 22,911, dated November 14, 1893.

Application filed December 15, 1892. Serial No. 455,306. Term of patent 7 years.

To all whom it may concern:

Be it known that I, JOHN F. MYERS, of San Francisco, California, have invented and produced a Design for a Lamp-Stove, of which the following is a specification.

My invention relates to a new and novel design for portable lamp stoves. It consists of a semi-cylindrical body marked A in the accompanying drawing mounted vertically on a base B, which is supported by legs C. The upper part of the body is cylindrical and supports an ornamental top D. The cylindrical

upper part of the body forms a hood, and also supports the ornamental top.

What I claim is—

The design for a lamp stove, consisting of a semi-cylindrical body with open front; a cylindrical top surmounting the semi-cylindrical body, and an ornamental top piece, all as herein shown and described.

JOHN F. MYERS.
